UNITED STATES PATENT OFFICE.

WILLIAM VON BRENNERBERG, OF NEW YORK, N. Y.

DESIGN FOR A NECKTIE.

SPECIFICATION forming part of Design No. 18,670, dated October 2, 1888.

Application filed August 18, 1888. Serial No. 283,131. Term of patent 14 years.

To all whom it may concern:

Be it known that I, WILLIAM VON BRENNERBERG, of the city, county, and State of New York, have invented and produced a new 5 and original Design for Neckties, of which the following is a specification, reference being had to the accompanying drawing, forming part thereof, which shows a face view of the necktie.

10 This invention relates to a design for neckties.

The design consists of a dark field, 1, resembling the side of the keystone of an arch, and containing illuminated or light stars, 2.

15 Extending downward in opposite diagonal directions from the lower end of the field 1

are two narrow bands, 3, overlapping each other lengthwise, the top of the upper band extending across the lower end of the field 1. The bands 3 contain a series of alternating 20 dark and light stripes, 4, running lengthwise thereof.

I claim—

The design for a necktie herein described and shown, consisting of the dark keystone-shaped field having light stars and the two depending bands containing dark and light longitudinal stripes. 25

WILLIAM VON BRENNERBERG.
